(57) **CLAIM**

The ornamental design for a repeater for wireless communication, as shown and described.

DESCRIPTION

FIG. 1 is a front perspective view of a repeater for wireless communication showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom thereof; and,

FIG. 8 is another front view thereof, in which an antenna in

broken lines is provided to illustrate an example environment.

The broken lines shown in the drawings that are immediately adjacent to the shaded areas, and define an unshaded region, represent the bounds of the claim, while the broken lines within the boundaries are directed to environment. The broken lines and the unshaded regions form no part of the claimed design.
